CLAIM

The ornamental design for an inspection camera, as shown and described.

DESCRIPTION

FIG. 1 is a front perspective view of an inspection camera showing my new design;

FIG. 2 is a front view thereof;

FIG. 3 is a rear view thereof;

FIG. 4 is a top view thereof;

FIG. 5 is a bottom view thereof; and,

FIG. 6 is a left side view thereof; the right side view being a mirror image thereof.

The broken lines depict portions of the inspection camera in which the design is embodied that form no part of the claimed design.
